UNITED STATES PATENT OFFICE

156,793

VANITY HAMPER

Pauline Wilks, Oakland, Calif.

Application December 22, 1947, Serial No. 143,269

Term of patent 3½ years

(Cl. D33—6)

To all whom it may concern:

Be it known that I, Pauline Wilks, a citizen of the United States and a resident of Oakland, county of Alameda, and State of California, have invented a new, original, and ornamental Design for a Vanity Hamper, of which the following is a specification, reference being had to the accompanying drawing, forming part thereof.

I claim:

The ornamental design for a vanity hamper, substantially as shown.

PAULINE WILKS.
